Des. 187,799
Patented May 3, 1960

187,799

TABLE OR THE LIKE

Eero Saarinen, Bloomfield Hills, Mich.

Application May 3, 1957, Serial No. 46,004

Term of patent 14 years

(Cl. D33—14)

Fig. 1.

Fig. 2.

Fig. 1 is a perspective view of a table embodying the new design; and

Fig. 2 is an elevational view of the table of Fig. 1. The dominant features of my design reside in those portions shown in full lines in the drawing.

I claim:

The ornamental design for a table or the like, as shown and described.
